UNITED STATES PATENT OFFICE.

EDWARD L. PITT AND EDWARD J. RUTHMAN, OF CINCINNATI, OHIO.

REVOLVING DISPLAY DEVICE.

1,265,376.

Specification of Letters Patent.

Patented May 7, 1918.

Application filed August 11, 1917. Serial No. 185,753.

To all whom it may concern:

Be it known that we, EDWARD L. PITT and EDWARD J. RUTHMAN, citizens of the United States, residing at Cincinnati, in the county 5 of Hamilton and State of Ohio, have jointly invented certain new and useful Improvements in Revolving Display Devices, of which the following is a specification.

It is the object of our invention to provide 10 a novel display device of simple and economical construction, comprising few parts and arranged to be readily assembled, and operating in such manner as to be rotated by currents of air applied thereto; and further, to provide the device with vanes arranged to have a suitable emblem repeated thereon so that when the vanes are rotated, the vision of one will merge into that of the other in order to observe the revolving 15 20 emblems as a continuous emblem.

The invention will be further readily understood from the following description and claims, and from the drawing, in which latter:

25 Figure 1 is a front elevation of our improved device as applied to an automobile, the latter partly broken away.

Fig. 2 is a front elevation of our improved device, with the stem and forward vane 30 partly broken away.

Fig. 3 is a plan view of the same.

Fig. 4 is an axial section of the same, taken on the line 4—4 of Fig. 3.

Fig. 5 is a cross-section of the same taken 35 in the plane of the line 5—5 of Fig. 4; and,

Fig. 6 is a perspective view of the parts of our improved device in separated relation.

Our improved device comprises vanes 11, of which a suitable number are employed, 40 these vanes being preferably duplicates of one another. They are formed out of suitable material, preferably thin sheet metal, bent to form a concave side 12 and a convex side 13. The inner end of the vane is formed 45 with a preferably reverse curl 14, the curl being preferably less than a circle in cross-section for forming a longitudinal slot 15 between the inner edge of the vane and the face of the vane toward which said edge 50 projects.

The vanes are assembled by having the curl of one vane received in the curl in a neighboring vane, which may be accomplished by hooking one curl within the other, preferably by endwise movement of 55 said curls lengthwise of one another. Other manners of assembling, for instance the lateral hooking of one curl in the other, are within the scope of our invention.

The vanes are preferably duplicates of 60 one another, so that when the curls of the assembled vanes are connected, the natural resilience in the metal will be sufficient to frictionally hold the vanes in assembled relation. The vanes extend substantially radi- 65 ally with relation to each other, four vanes being shown, the outer ends of which are equidistant from each other.

A step-bearing 16 is received in one end of the assembled curls, preferably the top 70 end. This step-bearing is in the form of a plug and is provided with a central bearing recess 17, the wall of which preferably tapers toward the axis of the device. The outer periphery of the bearing-plug is pref- 75 erably tapered at its recessed end, as shown at 18, for being readily received in the central bore 19 within the curls of the vanes and pushed axially therein so that the cylindrical portion of the bearing-plug is firmly 80 frictionally held within the inner curl. The bearing-plug is preferably provided with a shoulder 20 received over the telescoped ends of the curls, and is also preferably pro- 85 vided with a knob 21, which adds a finished appearance to the upper part of the device. The parts thus assembled are frictionally held together and form a rigid structure.

A stem 22 is arranged to be suitably secured to any part to which it is desired to 90 attach the device as, for instance, to the radiator of an automobile, part of which is shown at 23. The manner of securing can be accomplished in any suitable manner, as by fixing the stem to the usual screw-cap 95 24 of the radiator.

The stem is provided with a tapering end 25, preferably forming a point journal received in the recess 17 of the step-bearing. The stem is preferably of less diameter than 100

the diameter of the central bore in the assembled curls of the vanes. A bushing 26 is received in that end of the central bore of the curls of the vanes opposite the bearing- 5 plug and is arranged to form a radial bearing for the stem. The outer periphery of its inner end is preferably tapered as shown at 27 for being readily received in said bore.

The stem is provided with a retaining 10 part 28, arranged to be received between the bearing-plug and the bushing for retaining the parts together when assembled. This retaining part is exemplified as a spiral spring received about the stem, the spring being preferably forcibly slipped along the 15 stem to its proper position and frictionally held in place thereon.

In assembling parts, the curls of the vanes are received one within the other and the 20 bearing-plug forced into one end of the central bore of the curls. The bushing is placed about the stem below the retaining part and the pointed end of the stem, the retaining part and the bushing in assembled relation 25 are pushed into the central bore of the curls of the vanes from the opposite end of said bore, the bushing being forced into the central bore and held frictionally by pressure between the curls of the vanes and said 30 bushing.

The parts being now assembled, and the stem being held in upright relation, the pointed end of the stem receives lodgment within the bearing-recess of the bearing- 35 plug and the bushing forms a lower radial bearing for the vanes, this radial bearing being preferably, however, a loose bearing, so that the support of the assembled vanes is on the point of the stem forming bearing 40 means offering little frictional resistance to the rotation of the assembled vanes. When assembled, the retaining part is preferably slightly spaced from the lower bushing, as shown by the space 29.

45 The respective sides of the vanes may be provided with a suitable emblem, preferably reversely placed on the opposite sides of the vanes, and each of the vanes is preferably provided with a similar emblem similarly 50 placed. The emblem shown in the drawing is a representation of the United States flag, the emblem on the device in practice showing the flag in its usual colors.

When now the device is subjected to a 55 current of air, caused for instance by the movement of the automobile, when attached to an automobile, or by the directing of currents of an electric fan against the device, or in other suitable manner, the current of 60 air is pocketed in the concave sides of the vanes and deflected by the convex sides of the vanes, so as to cause rotation of the assembled vanes with that side of the device having the concave sides of the vanes pre-

sented toward the current of air moving re- 65 cedingly from said current, the structure being such that a very slight current of air will cause rotation of the vanes.

The emblem is placed in opposed relation on opposite sides of each of the vanes, the 70 upper portions of the emblems being at the upper portions of each of the sides, and the head ends of the emblems being positioned toward the inner ends of the vanes.

The rotation of the vanes causes a repeti- 75 tion of the emblem to be brought to the view of the observer, the emblems on succeeding vanes and on the reverse sides of the vanes appearing as continuations of one another for forming a continuous vision of the 80 emblem.

Having thus fully described our invention, what we claim as new and desire to secure by Letters Patent is:

1. A revolving display device comprising 85 vanes having means thereon telescoping one within the other and a bearing for the assembled vanes received in said means.

2. A revolving display device comprising 90 a plurality of vanes, said vanes provided with curls at their inner ends, said curls received one in the other for assembling said vanes, a stem, and a step-bearing between said assembled vanes and said stem.

3. A revolving display device of the character described comprising vanes having curled edges forming bores, said curls received one within the other for forming a central bore, a bearing-plug received in one end of said central bore, and a supporting 100 stem received in said central bore, said supporting stem having bearing with said bearing-plug.

4. A revolving display device of the character described comprising vanes, said re- 105 spective vanes having a concave face and a convex face and a curl at the inner end thereof, said curls received one within the other and forming a central bore, the bodies of said vanes extending substantially equi- 110 distant from each other, a bearing-plug pro- vided with a recess at its inner end, said bearing-plug received endwise in one end of said bore, a supporting stem having a retaining part thereon, and a bushing held in 115 the other end of said bore, said stem located in said bushing, said retaining part located between said bushing and said bearing-plug, and the end of said stem being reduced and having bearing in said recess.

5. A revolving display device comprising 120 vanes respectively provided with curled inner ends, said vanes assembled with their outer ends substantially equidistant from each other and said curled inner ends tele- 125 scoped one within the other for frictionally maintaining their relation and forming a central bore, a bearing-plug frictionally re-

ceived in one end of said bore, a stem provided with a retaining part received in said bore, said stem and bearing-plug provided with a step-bearing between them, and a bushing frictionally received in said bore about said stem under said retaining-part.

5 In testimony whereof, we have hereunto

signed our names in the presence of two subscribing witnesses.
